UNITED STATES PATENT OFFICE

GABRIEL CLARK WILLIAMS, OF ALLIGATOR, MISSISSIPPI

BACKBAND BUCKLE

Application filed July 18, 1930. Serial No. 468,831.

This invention relates to back band buckles and brace carriers and the object of the invention is to provide a strong and durable back band buckle having approximately twice the gripping means of the ordinary back band buckle and provided with novel pivoted hooks to carry the trace designed to ease the strain upon the buckle and chafing of the body of the animal upon which said buckle may be mounted.

It is also an object of this invention to provide a buckle of the character described composed of two main parts, each of said main parts being stamped or struck out from single blanks, thus making them simple and inexpensive to manufacture.

These and other objects, the nature of the invention, its combination, its composition, and arrangements of parts will be clearly understood from a reading of the accompanying drawings and the description thereof.

In the drawings:

Figure 1 represents a plan view of the double back band buckle of the invention.

Figure 2 shows a modification of the invention providing single back band gripping elements.

Figure 3 shows one form of the pivoted trace hook, and

Figure 4 shows another form of pivoted trace hook having dual hooks thereon.

It will be understood that I do not desire to limit the application of this invention to the particular modifications set out herein in illustration, and any change or changes in material and structure may be made within the scope of the invention.

Referring to the drawings in detail, it will be seen that a generally rectangular plate 5 having rectangular recesses cut in the opposite ends thereof. Cut or punched through this central portion thereof is a rectangular recess 7 having its ends and sides parallel to the ends and sides of the

blank. Near the edges of the longitudinal sides 8 and 9 of the blank are cut or punched long slots 10 and 11 extending substantially the length of said longitudinal sides, adapted to receive the back band and retain the same against withdrawal.

Holes 12 are provided in the blank to accommodate rivets or the like for attaching the buckle to the leather or other back band or to a wagon breeching. Centrally and immediately below the lower slot 10 in the plate is a pivot 13 on which is pivoted a trace carrier hook 14 comprising an irregular, symmetrical plate adapted to be pivoted on said pivot 13, the central portion of said plate being punched out to provide a hook 15 and ears 16 for mounting and retaining one of the links of the trace chain and for preventing the accidentally dislodgment of the chain therefrom.

The pivoted mounting of the trace carrier provides for the free movement of the chain without undue strain upon the buckle and to prevent the chafing of the animal upon which said back band buckle is mounted. A retaining bar 17 is punched out from the part above the top slot 11 and provides a retaining means against which the bottom of the trace carrying assembly slides in its pivoting motion and the bar 18 bounding the bottom of the recess 7 and the back retaining member through which the assembly 14 slides, said assembly being retained by the ends of said bar 17 from complete rotation on its pivot.

The link of the trace chain is required to be entered upon the hook 15 in endwise manner and when slipped down upon said hook is retained against dislodgment from said hook by the ears 16 projecting inwardly from the plate 14.

A modification of the device in Figure 1 is shown in Figure 2, the device of Figure 2 having but one set of back band receiving slots 10.

Another modification of the trace carrier hook assembly is shown in Figure 3 and set out in Figure 4. In the Figure 4, the modification consists of a plate 19 having a square bottom and a curved top portion having a pivot hole 20 and laterally extending arms 21 formed integral with the body 19 and right angularly projecting hooks 22 mounted adjacent the end edges of said arm 21. Like the trace carrying hook assembly shown in Figure 3 and operated as the device in Figure 1, the modification of the device of Figure 4 is adapted to be pivoted at 13 and the trace chain link seated in the hook 22 and it otherwise functions similarly to the trace carrier hook assembly already described.

It will now be evident that I have provided a backband buckle having back band securing bars and slots and a pivoted trace carrying assembly of simple and inexpensive construction which provides a non-chafing and non-slipping backband buckle of superior adaptability to the purpose for which it is designed, and which can be manufactured and distributed at a low cost.

I claim:

1. A back band buckle comprising a rectangular plate, parallel longitudinal slots near each longitudinal edge of said plate, a large cut-out portion centrally disposed in said plate, a trace carrying hook of roughly triangular form pivoted at its apex to one side of the plate adjacent one longitudinal edge of said cut-out portion, and a bar struck out from the opposite longitudinal edge portion of said plate adjacent said cut-out portion adapted to engage the lower end of said trace carrying hook assembly and to prevent the complete rotation of the same.

2. A back band buckle of the type described, comprising a rectangular plate having spaced parallel longitudinal slots near its upper longitudinal edge, a wide cut-out portion disposed longitudinally below said slot, a bar struck out laterally from the lower edge portion of the plate, a substantially triangular plate constituting a trace carrying assembly, a pivot secured centrally on the upper edge of the wide cut-out portion adapted to pivot said trace carrying assembly, a hook cut-out of said assembly, and ears cut out of said assembly and associated with said hook to retain a trace chain on the hook, the pivotal motion of said assembly being restricted by said bar struck out from the bottom edge of the plate.

3. A back band buckle of the type described, comprising a rectangular plate having spaced parallel longitudinally disposed slots along each of said longitudinal edges, a central cut out portion being disposed in said plate, a bar struck out laterally from a point near the longitudinal and lower

edge of said cut out portion, a pivoted plate, a pivot attached adjacent the upper longitudinal edge of said struck out portion to form said pivoted plate, said struck out bar adapted to co-operate with the lower portion of the pivoted plate and to limit the pivotal movement thereof, and hook means associated with said pivoted plate to receive and retain the links of a trace chain or the like.

In testimony whereof I affix my signature.

GABRIEL CLARK WILLIAMS.
